(57) **CLAIM**

The ornamental design for a package for a container and oral appliance, as shown and described.

DESCRIPTION

FIG. 1 is a front perspective view of a package for a container and oral appliance showing my new design;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top plan view thereof; and,
FIG. 7 is a bottom plan view thereof.

The evenly spaced dashed broken lines in the figures illustrate portions of the package, container and oral appliance that form no part of the claimed design.

The unevenly spaced dot-dash broken lines in the figures define the boundaries of the claimed design and form no part thereof.
